UNITED STATES PATENT OFFICE.

CHARLES JOHN NOKE, OF BURSLEM, ENGLAND, ASSIGNOR TO HENRY DOULTON, OF LONDON, ENGLAND.

DESIGN FOR A VASE.

SPECIFICATION forming part of Design No. 27,883, dated November 23, 1897.

Application filed September 2, 1897. Serial No. 650,401. Term of patent 7 years.

To all whom it may concern:

Be it known that I, CHARLES JOHN NOKE, a subject of the Queen of Great Britain and Ireland, residing at Burslem, in the county of Stafford, England, have invented a new and useful Design for a Vase, of which the following is a specification.

The design for which I desire to secure a patent is shown in the annexed drawing.

It relates to a vase made of earthenware, and its special and distinctive features are the slender neck A, rising from the globular body B, terminating in the leaf-like "lip" or spout C and provided with the curved and

tapering handle D, extending from the body 15 B to a point immediately below the opening of the spout.

Having thus described my new and original design, I declare that what I claim is—

The design for a vase, as herein shown and described.

In witness whereof I have hereunto set my hand in the presence of two witnesses.

CHARLES JOHN NOKE.

Witnesses:

JOHN W. LATIMER,
EDWARD TUSHINGHAM.
